US0D1094127S

(12) **United States Design Patent** (10) **Patent No.:** **US D1,094,127 S**
(45) **Date of Patent:** **** Sep. 23, 2025**

(54) **MOTION SENSOR**

(71) Applicant: **Amazon Technologies, Inc.**, Seattle, WA (US)

(72) Inventors: **James Siminoff**, Pacific Palisades, CA (US); **Mark D. Siminoff**, Mountain View, CA (US); **Wen-Yo Lu**, Pasadena, CA (US); **Christopher Loew**, Palo Alto, CA (US); **Jia Li**, Nutley, NJ (US); **Wei-Chung Wang**, New Taipei (TW); **Gregory Berlin**, Spring City, PA (US); **Andrew Louis Russell**, Havertown, PA (US); **Eric Scott Micko**, San Jose, CA (US)

(73) Assignee: **Amazon Technologies, Inc.**, Seattle, WA (US)

(**) Term: **15 Years**

(21) Appl. No.: **29/927,857**

(22) Filed: **Feb. 6, 2024**

Related U.S. Application Data

(60) Continuation of application No. 29/825,923, filed on Feb. 7, 2022, now Pat. No. Des. 1,019,433, which is a division of application No. 29/714,035, filed on Nov. 20, 2019, now Pat. No. Des. 942,881.

CLAIM

The ornamental design for a motion sensor, as shown and described.

DESCRIPTION

FIG. 1 is a top, front, right-side perspective view of a motion sensor;

FIG. 2 is a bottom, back, left-side perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The dashed broken lines depict portions of the motion sensor that form no part of the claimed design.

1 Claim, 8 Drawing Sheets
